UNITED STATES PATENT OFFICE.

CARL E. WENZEL, OF NEWARK, NEW JERSEY.

DETONATING TOY.

SPECIFICATION forming part of Letters Patent No. 738,585, dated September 8, 1903.

Application filed December 22, 1902. Serial No. 136,121. (No model.)

To all whom it may concern:

Be it known that I, CARL E. WENZEL, a citizen of the United States, residing at Newark, in the county of Essex and State of New Jersey, have invented and produced a new and original Improvement in Detonating Toys; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The objects of this invention are to secure in a detonating toy improved means for holding the caps in position, such as will enable the strip containing said caps to be fed into position conveniently, to provide an improved 20 construction of such toys, and to obtain other advantages and results, some of which will be hereinafter referred to in connection with the description of the working parts.

The invention consists in the improved detonating toy and in the arrangements and combinations of parts of the same, all substantially as will be hereinafter set forth and finally embraced in the clauses of the claim.

Referring to the accompanying drawings, 30 in which like letters of reference indicate corresponding parts in each of the several figures, Figure 1 shows in perspective a toy of my improved construction subsequent to the act of firing and with a strip of caps in position. Fig. 2 is a plan of the same, and Fig. 3 is a vertical section taken longitudinally and centrally of the toy.

In said drawings, 22 indicate the side plates or pieces of the frame of my improved detonating toy, and 3 is the body part supported thereby and which is preferably in the form of a cannon, as shown. Each side plate 2 forms at its bottom edge an extended bearing 4 to engage the ground or floor, and lateral lugs 5 may be provided adjacent to said bottom edge, as shown in Fig. 2, to receive fastening-screws, if desired.

The two side-plates 22 and the cannon or body 3 are all cast, preferably, in two castings, the division being vertically and longitudinally of the body, so that one side plate

and one-half of the body or cannon are integral. Rivets 6 are then passed through the two halves or they may be connected in any other suitable manner.

55

At the rear end of the cannon 3 an anvil 7 is formed, against which explosive caps may be placed, a perforation 8 extending from the face of the said anvil to the interior of the cannon to receive smoke. From the lower edge of said anvil arms 9 project upward, one near each edge of the anvil, to hold the cap. Said arms 9 lie a little distance away from the anvil, so as to provide a slideway or space into which a strip 10 of caps may be slid 65 edgewise. This strip can then be fed along by hand as needed, and at the same time the engagement of the arms 9 9 is sufficient to hold the strip during explosions. A hammer 11, adapted at its upper end to engage the 70 said anvil, is mounted at its lower end upon a cross-shaft 12, having its ends supported by the side plates 22. A spring 13, coiled upon said shaft and engaging at its ends the hammer and frame 2, respectively, serves to normally throw said hammer against the anvil. To retract said hammer and automatically release the same for its forward stroke, I have provided the means shown in my prior application, Serial No. 128,364, filed October 22, 75 1902, comprising an operating-lever 14, fulcrumed at its lower end upon one side plate 2 of the frame, as at 15, and provided at its inner side with transverse recesses or grooves 16 17, adapted to receive the end of a finger 80 18, projecting laterally from the hammer. The lower groove is inclined at its bottom forwardly, and thus adapted to pass the finger end from behind, but to carry the hammer with itself on a backward swing until 85 90 said finger, sliding on the lever, arrives at the upper groove 17, through which it escapes for a forward stroke, all as described in detail in my prior application above referred to.

Having thus described the invention, what I claim as new is—

1. In a detonating toy, a body portion providing at its end an anvil having a vertical face and having parallel to the face of said anvil a narrow transverse capway closed at its bottom and open at its top, a spring-controlled hammer adapted to engage said anvil,

and an operating-lever adapted to swing across the plane of said capway.

2. In a detonating toy, a body portion providing at its end an anvil having a vertical face and having parallel to the face of said anvil a narrow transverse capway closed at its bottom and open at one lateral side to receive the end of a strip of caps, a hammer adapted to engage said anvil, and an operating-lever adapted to swing across the plane

of said capway on the opposite side thereof from the said open side.

In testimony that I claim the foregoing I have hereunto set my hand this 15th day of December, 1902.

CARL E. WENZEL.
